Application June 1, 1927. Serial No. 195,689

17 Claims. (Cl. 219—10)

This invention relates to the making of butt joined tubes and pipes, and has for its prime object to provide an improved apparatus for the continuous production of a tubular shape from a cold metal strip or blank which is first subjected to a series of operations and thereby formed into a tube with the edges of the blank in abutted relation, immediately after which the abutted edges of the blank are electrically joined, the finished tube being subsequently straightened and cut into lengths. The tube is fed to and through the electric apparatus by means of the traveling movement imparted to the tube by the action of the rolls employed in shaping the blank into tubular form, and the capacity of the electric apparatus is such as to produce an efficient joint at the rate of speed imparted to the tube by the rolls of the tube forming machine or apparatus.

5 The invention has been illustrated in the accompanying drawings wherein,

Figure 1 is a side elevation, more or less diagrammatic and partly in section, of a tube shaping and joint forming apparatus embodying the 10 features of the present invention;

Figure 2 is a cross sectional view of a tube blank having its longitudinal edges bevelled by the first pass of the tube forming machine;

Figure 3 is a similar view showing the plate 15 having its bevelled edges bent into flanges projecting at that side of the blank which is to be the exterior of the tube;

Figures 4, 5, 6, 7 and 8 are views of the blank 20 in its successive stages of formation;

Figure 9 is an enlarged fragmentary detail 25 view of the rolls employed for beveling the edges of the blank;

Figure 10 is an enlarged detail fragmentary 30 view showing the arrangement of the rolls for bending the flanged edges of the blank;

Figure 11 is an enlarged cross sectional view 35 of a portion of the electric apparatus;

Figure 12 is a detail fragmentary plan view 40 of Figure 11;

Figure 13 is a side elevation of Figure 12;

Figures 14 and 15 are enlarged fragmentary 45 views showing the cooperative relation between the seam of the tube and one of the electrodes of the electric welding apparatus; and

Figure 16 is a detail fragmentary view showing 50 one of the side electrode rolls and its mounting.

The apparatus of the present invention includes a tube shaping or forming apparatus designated in general by the reference character A,

and an electric apparatus designated in general by the reference character B, the two machines being arranged in close proximity to one another so that the electric machine may receive the tubular shape immediately as it is fed from the tube shaping machine. The tube making machine is provided with pairs or sets of cooperating rolls for performing the successive bending or shaping operations upon the blank, and said rolls are arranged to produce the successive passes which have been designated 2, 3, 4, 5, 6, 7 and 8, through which the blank is continuously fed and shaped to the final product.

In order that the operation may be a continuous one, it is proposed to have the cold blank C put up in a roll or coil D which is mounted upon a suitably supported reel E. Located between the reel E and the feed-in end of the tube shaping machine A, there is a suitable track 10 supported in a horizontal position in any suitable manner as upon leg standards 11. The track 10 is below the horizontal line of the passes of the tube shaping machine and supports a carriage 12 mounted to travel back and forth on the track and beneath the horizontal line of the passes. Suitable clamping devices 13 and 14 are provided upon the carriage so as to clamp thereupon the rear end of one tube blank and the front end of another tube blank with said ends in abutted relation so that they may be welded by any suitable means, as for instance by a gas torch 15 carried by a carriage. It will of course be understood that any form of welding means may be employed, as the form of the welding means constitutes no part of the present invention. The clamps 13 and 14 are hand operated, and are manually released just before the carriage reaches the end of the track adjacent the tube forming machine, and the carriage is returned to its original position by a weight 16 and a cord 17 connected to the carriage and travelling over a guide pulley 18.

As the tube blank C travels through pass 2, its longitudinal edges are provided with the bevels 19 as shown in Figures 2 and 9. The pass designated 2 is defined by a lower horizontally disposed plain faced roll 20, and an upper composite roll consists of a cylindrical plain faced roll 21 and end roll sections 22 of greater diameter than the intermediate roll section 21 and provided with inner bevelled end portions 23. The lower roll 20 embraces a noncircular portion of a shaft 24 having a fixed annular collar or shoulder 25 against which one end of the roll 20 is held by means of nuts 26 provided upon the screw threaded portion 27 of the shaft 24. Similarly the upper

roll sections embrace a non-circular portion of a shaft 28 having a collar 29 against which one end of the composite roll is held by means of nuts 30 fitting the screw threaded portion 31 of the shaft. By this construction, the roll parts may be replaced when worn and may be substituted by different sizes of parts in accordance with the thickness and width of the tube blank and the character of the bevel to be produced upon the 10 blank.

Immediately upon being fed out of the pass designated 2, the bevelled tube blank is fed into the pass designated 3 and its bevelled edges bent into flanges 32, as shown in Figures 3 and 10, 15 said flanges being projected at the lower side of the blank which is to be the exterior of the finished tube in its final form. The pass designated 3, as shown in Figure 10, is made up of an upper plain faced cylindrical roll 33 mounted on 20 a horizontal axis, a lower plain faced cylindrical roll 34 having its ends bevelled as at 35 and mounted upon a horizontal axis below and in alignment with the roll 33, and a pair of opposite rolls 36 and 37 mounted upon vertical axis in 25 the same plane with the axis of the roll 33 and 34, and provided with the bevelled faced portions 38 and 39, which, together with the bevelled end portion 35 of the lower roll 34 bend and shape the bevelled edges of the blank C into the flange 32.

The succeeding passes 4, 5, 6, 7 and 8 shape the blank progressively in accordance with Figures 4, 5, 6, 7 and 8 of the drawings. It will therefore be understood that as the blank emerges from the last pass designated 8 it will have been bent into 35 the tubular shape C' shown in Figures 8 and 14 with its bevelled edges 19 in partially abutted relation and the flanges 32 disposed longitudinally of the tube on the exterior thereof. The bevelled or inclined edges 19 of the blank do not abut 40 throughout their widths, but come together at their outer end portions only, thereby leaving a substantially V-shaped space between the abutted edges of the blank at the inner side of the tube. The two flanges 32 constitute an external rib extending longitudinally of the tube and of V-shape 45 in cross section. It will here be noted, as best shown in Figure 14 of the drawings, that the widest dimension *a* of the combined ribs or flanges 32 at the exterior of the tube is less than the thickness *b* of the blank for an important purpose 50 as will be hereinafter explained.

Immediately after the tubular shaped blank emerges from the last pass 8, it is subjected to the action of the electric machine for the purpose of 55 fusing the external rib, so that fused portions thereof may flow downwardly and fill the gap between the lower portions of the spaced edges 19 of the blank and thereby join such edges in a simple and efficient manner. The tubular shape 60 is fed to the electric apparatus by reason of the travel of the blank through the tube forming machine, whereby the tube forming machine and the electric machine operate successively and continuously upon a single blank as it is travelling 65 through the apparatus under the feeding effect of the driven rolls of the tube forming machine.

The tubular shape C', in the cross sectional shape shown in Figure 8, travels from the last pass 8 of the tube forming machine into the electric machine and between the cooperating idle-rolls 40 and 41, Figures 11, 12 and 16, which have concaved peripheries so as to define a seat or pass for the tube C'. The mountings for the rolls 40 and 41 are duplicates, and therefore a description of one of the mountings is deemed sufficient. 75

Each of these rolls is carried by an upstanding rotatable spindle 42 mounted in upper and lower bearings 43 and 44 carried by a bracket 45, pivoted at its lower end as at 46 upon a hanger 47 secured to and depending from a part 48 of the frame of the machine. By the pivotal mounting of the bracket 45, the rolls 40 and 41 may be adjusted towards and away from one another to vary the size of the pass or gap between the rolls for the purpose of accommodating tubes of different diameters. For convenience in adjusting the positions of the rolls 40 and 41, there is provided a horizontal and rotatable adjusting member 49 which is mounted between its ends in a suitable bearing 50 carried by the hanger 47 and located between the pivotally adjustable brackets 45. The respective end portions of the rotatable bar 49 are reversely screw threaded, and each end portion is received within a nut 51, best shown in Figure 16 of the drawings, said nut having trunnions 52, received respectively in a bearing opening 53 in the pivoted bracket 45 and the substantially L-shaped bracket 54 provided upon the front face of the pivotal bracket 45, whereby the nuts 51 will remain in a horizontal position with the adjusting rod 49 and thereby accommodate themselves to the tilting adjustments of the pivotal brackets 45. A detachable crank handle 55, or other suitable means, may be employed for rotating the rod 49 to adjust the positions of the 103 pivotal bracket members 45.

Each roll spindle 42 extends below the lower bearing bracket 44 and dips into a mercury bath contained in a cup or receptacle 56 which is carried by a cross head 57 bolted or otherwise secured to one of the pole terminals 58 of the secondary 59 of any suitable form of electric transformer. The lower end portion of the spindle which is within the bath is grooved, either circumferentially, as shown, or longitudinally, so as to expose a large surface area to the mercury contained in the cup or receptacle 56. The internal diameter of the cup or receptacle 56 is such as to permit of the necessary tilting of the spindle 42 in the adjustments thereof. It will now be understood that the rolls 40 and 41 are electrically connected to the pole piece 58 through their spindles 42 and the mercury contents of the cups or receptacles 56, and therefore the rolls 40 and 41 constitute one of the pole members of the 125 welding machine.

Disposed horizontally and diametrically across the tops of the rolls 40 and 41 is the other pole member 60 of the electric machine, said pole member being in the form of a cylindrical roll or bar provided at its middle with a band or collar 61 preferably of copper and disposed so as to come into proper cooperative relation with the rib on the exterior of the tubular shape C'. Each end of the member 60 is provided with a journal 62 rotatable within an anti-friction bearing 63 carried by and insulated from a substantially horizontal link or arm 64 pivoted upon an upstanding bracket arm 65 rising from a frame portion 66 of the machine. As best shown in Figure 12, it will be seen that the brackets 65 are connected by a base member 67 mounted to slide endwise in a guideway 68 provided upon the top of the frame portion 66. The opposite arms or links 64 are connected by a rod or bar 69 rotatably mounted in the bracket 65 so that the two arms 64 are connected for simultaneous up and down movements. Downward movement of each arm 64 is limited by means of a shoulder 70 depending from the arm and disposed for engagement 140

with a set screw 71 carried in a screw threaded boss 72 provided upon the outer face of the adjacent post or bracket 65. Under operating conditions, and as well shown in Figures 14 and 15 of the drawings, it will be seen that the pole member 61 rests upon the tubular shape C' and against the rib 32 and supports the arms 64 in the position indicated in Figure 13 with the part 70 slightly in advance of the set screw 71. When there is no work in the machine, the part 70 engages the forward end of the set screw 71 so as to maintain the pole piece 61 in proper position for engagement with the external rib of a tubular shape which is being entered into the welding machine.

It is proposed to longitudinally reciprocate the pole member 60 so as to work the pole piece 61 transversely across the rib on the tube and thereby prevent the wearing of a groove in the periphery of the pole piece 61. To accomplish this result, the base member 67 is reciprocated endwise through the medium of an oscillating arm 73 fulcrumed as at 74 upon the frame part 66 and connected at one end by means of a pivotal link 75 with the base member 67. The other end of the arm 73 is slotted at 76 to receive a wrist pin 77 carried by an eccentric 78 mounted upon the frame part 66 and suitably driven from some operating part of the general apparatus.

As best shown in Figure 11 of the drawings, it will be seen that each end of the pole member 60 is provided with a circular head 79, grooved peripherally as at 80, and having its lower portion dipped into a mercury bath in a mercury cup or container 81 carried by the upper end of an arm standard 82 rising from the cross head 83 suitably secured to the other pole piece 84 of the secondary 59, whereby the electric circuit will be completed from the tubular shape C' through the pole member 60, the heads 79, the standards 82 and the cross head 83.

After passing from the electric machine, the tube C² passes through a finishing and straightening machine F of any ordinary or preferred form. As shown in Figure 1 of the drawings, the machine F includes finishing rolls 85 for smoothing the exterior of the pipe, and bending rolls 86 for straightening the tube or pipe. After passing from the finishing and straightening machine F, the tube or pipe is run into any desired form of tube cutting machine, not shown, for the purpose of cutting the finished tube into lengths.

The action of the electric machine will be best understood by reference to Figures 11, 12, 14 and 15 of the drawings. In the beginning of the operation, as well shown in Figure 11 the pole piece 61 rests upon the apex of the pointed external rib 32 on the tubular shape C', whereby the tip edge of the rib becomes fused and the pole piece sinks down into the rib to about the position shown in Figures 14 and 15 of the drawings, whereby the rib will be fused throughout substantially its entire depth as the tubular shape is fed through the machine under the feeding influence of the driven rolls of the tube shaping machine A. Under operating conditions, the weight of the pole piece 60 and its associated parts is supported upon the tubular shape C', as shown in Figs. 14 and 15, and as the latter is supported in the seat defined by the rolls 40 and 41 there is no pressure exerted to force the spaced edges of the blank together such as is commonly employed in welding operations. The pole member 60 will be rotated by reason of the frictional engagement between the tubular shape

C' and the pole piece 61, while at the same time the pole member 60 will reciprocate transversely across the rib under the action of the oscillating arm 73. It will of course be understood that the size of the mercury cups 81 is sufficient to permit of the necessary lateral play of the contact head 79 in the mercury baths. As the rib 32 is fused, the molten metal runs down and fills the gap between the spaced edge portions 19 of the blank which produces a strong and durable joint without producing any internal rib on the completed tube while at the same time filling the gap between the edges of the blank without leaving a groove at the interior of the tube.

It will here be explained that there is no welding of the joint in the sense of softening metal members and then applying pressure thereto sufficient to unite the softened parts into a welded joint, for the reason that the fused parts of the flanges gravitate into the gap which is filled by the fused metal, and such fused metal when it hardens unites the edges of the blank in a strong and durable seam or joint.

The large dimension *a* of the combined flanges 32 is less than the thickness *b* of the blank or 100 the wall of the tube, whereby the electric current is concentrated in the combined flanges or rib and fusion is limited thereto, so that burning of the walls of the tube adjacent the butt weld is effectually prevented.

In the practice of the invention, and in order that it may be continuous, the tube blank C is in the form of a long strip of the desired thickness and width. For convenience in handling, the cold strip is wound into a coil, as indicated at D, 110 Figure 1, and mounted on the reel E. The end of the strip or blank is fed to the roll forming machine A and entered by hand into the bite of the driven rolls constituting the first pass designated 2, and thereafter the blank is fed automatically through the entire apparatus under the feeding action of the driven rolls of the tube forming machine A. It will of course be understood that the tube forming machine is driven in any suitable manner, as by an electric motor which 120 is of course regulable as to speed. As the blank passes through the tube forming machine, it is successively given the shapes shown in Figures 2 to 8 inclusive, and is fed directly from the last pass 8 into the electric machine and passes between the rolls 40 and 41 with the external rib 32 in frictional engagement with the pole piece 61 as best shown in Figure 11 of the drawings. Fusion and union of the edges of the blank takes place in the electric machine, as hereinbefore described, and thereafter the completed tube C² passes on to the finishing and straightening machine F and thence to a tube cutting machine, not shown, for the purpose of cutting the completed tubes into lengths.

From the foregoing explanation of the practice of the present invention, it will be understood that the tube shaping and the joint forming operations are performed successively and continuously upon the same strip of metal, and that the work emerges from the finishing and straightening machine in a smooth finished condition and is afterwards cut into lengths. The finished tube has neither external projections nor internal grooves. The manual labor expended is 140 reduced to the minimum.

By reason of the contact of the pole member 61 with the thin apex of the external rib 32, immediate and effective fusion of the relatively thin edge of the rib is obtained, which permits of the 150

formation of the seam as rapidly as the shape C' can be formed by the tube forming machine A and fed thereby to the electric machine. This rapid formation of the seam permits of the said operation following immediately upon the completion of the final step of the tube shaping operations, and therefore permits the operation of the tube shaping machine at its normal rate of speed. In actual practice, tubes have been made in accordance with the present invention at the rate of twenty feet per minute.

As hereinbefore explained overheating is prevented because of the triangular shape of the external rib 32, together with the fact that the width of the base of the rib is less than the thickness of the blank, so that the electric current is concentrated in said rib, and therefore burning of the blank adjacent the joint is impossible. Actual practice has shown that even great irregularities in the thickness of the blank or metal strip have no undesirable influence on the formation of the joint, and therefore it is possible to use crude, or so called hot or cold rolled metal strips which are seldom uniform in their dimensions. Moreover the electric current consumption is low, as the heat is concentrated at the fusion zone.

What is claimed is:

1. The herein described method of making metal tubes, which consists in feeding a continuous blank, beveling the longitudinal edges of the blank, bending the bevelled edges of the blank into flanges, bending the blank into tubular shape with the flanges on the exterior thereof and their outer edges in abutted relation and disposed to define a space between said flanges, each of said steps being performed while the blank is in motion, and progressively and continuously fusing the external flanges whereby the fused metal will run into and fill the space between and thereby unite the edges of the blank as fast as the tubular shape is produced.

2. The herein described continuous method of making metal tubes, which consists in continuously feeding a continuous blank at a uniform rate of speed, continuously and progressively beveling the longitudinal edges of the blank while it is being fed, continuously and progressively bending the bevelled edges of the blank into flanges during the feeding of the blank, continuously and progressively forming the blank into tubular shape with the flanges on the exterior of the shape and their outer edges in abutted relation and disposed to define a space between said flanges, each of said steps being performed while the blank is in motion, and continuously and progressively fusing the flanges whereby the fused metal will run into and fill the space between and thereby unite the edges of the blank as fast as the tubular shape is formed.

3. The herein described method of making metal tubes, which consists in beveling opposite edges of a blank, bending the bevelled edges into flanges, bending the blank into tubular shape with the flanges on the exterior of the shape and their outer edges in abutted relation and defining a triangular external rib whose base is less than the thickness of the blank, the bevelled edges of the blank defining a V-shaped gap therebetween, and electrically fusing the rib whereby the fused metal will be permitted to run into the V-shaped gap.

4. The herein described method of making metal tubes, which consists in beveling opposite edges of a blank, bending the bevelled edges into

flanges, bending the blank into tubular shape with the flanges on the exterior of the shape and defining a triangular rib with the outer edges of the flanges in abutted relation and the adjacent faces of the flanges diverging towards the interior of the tube and defining a gap, and electrically fusing the rib whereby the fused metal will be permitted to run down into the gap.

5. The herein described method of uniting metal parts which consists in beveling the parts, bending the bevelled parts into flanges, bringing the flange parts together with the outer edges of the flanges in abutted relation and their adjacent faces diverging and forming a gap, and electrically fusing the flanges whereby the fused metal will be permitted to run into the gap.

6. The herein described method of uniting metal parts which consists in beveling the parts, bending the bevelled parts into flanges, bringing the flange parts together with the outer ends of the flanges in abutted relation and their adjacent faces diverging and forming a gap, and fusing the flanges whereby the fused metal will be permitted to run into the gap.

7. The herein described method of uniting metal parts which consists in beveling the parts, bending the bevelled parts into flanges, bringing the flange parts together with the outer ends of the flanges in abutted relation and their adjacent faces diverging and constituting a gap, applying electrodes of opposite polarity to the parts with one of the electrodes applied to the outer edges of the flanges and thereby fusing the flanges and permitting the fused metal to run into the gap and unite the flanges, and effecting relative movement between the flanges, and the adjacent electrode in a direction transversely across the flanges.

8. The herein described method of uniting metal parts, which consists in beveling the parts, bending the bevelled parts into flanges, bringing the flange parts together with the outer ends of the flanges in abutted relation and their adjacent faces diverging and constituting a gap, applying electrodes of opposite polarity to the parts with one of the electrodes engaging the outer edges of the flanges and thereby fusing the flanges and permitting the fused metal to run into the gap and unite the flanges, and reciprocating said electrode transversely across the flanges.

9. The herein described method of making metal tubes, which consists in beveling opposite edges of a blank, bending the bevelled edges into flanges, bending the blank into tubular shape with the flanges on the exterior of the shape and defining a triangular rib with the outer edges of the flanges in abutted relation and the adjacent faces of the flanges diverging towards the interior of the tube and defining a gap, fusing the flanges and permitting the fused metal to run into the gap and unite the edges of the blank by applying electrodes of opposite polarity to the tube with one of the electrodes engaging the flanges, feeding the tube endwise past the electrodes, and reciprocating the electrode engaged with the flanges transversely thereof.

10. The herein described continuous method of forming tubes into lengths from a continuous blank, which consists in feeding a continuous blank through a series of roll passes formed by positively driven rolls and thereby beveling opposite edges of the blank, bending the bevelled edges into flanges, and bending the blank into tubular shape with the flanges on the exterior of the shape and defining a triangular rib with the

- outer edges of the flanges in abutted relation and the adjacent faces of the flanges diverging towards the interior of the tube and defining a gap, directing the moving and shaped blank directly 5 from the last pass to and between idle rotatable electrodes of opposite polarity with one of the electrodes in contact with the flanges and thereby fusing the flanges, and reciprocating said electrode transversely across the flanges, whereby 10 by the fused metal will run into the gap and there solidify and unite the edges of the blank.
11. The herein described method of uniting metal parts, which consists in bevelling the parts, bending the bevelled parts into flanges, bringing 15 the flange parts together with the outer ends of the flanges in abutted relation and their adjacent faces diverging and constituting a gap, including the work piece in an electric circuit with one contact made at the outer edges of the flanges and 20 thereby fusing the flanges and permitting the fused metal to run into the gap and unite the flanges, and effecting relative movement between the flanges and their points of contact with the electric circuit in a direction transversely across 25 the flanges.
12. The herein described method of uniting metal parts, which consists in bevelling the parts, bending the bevelled parts into flanges, bringing the flange parts together with the outer ends of 30 the flanges in abutted relation and their adjacent faces diverging and constituting a gap, including the work piece in an electric circuit with one contact made at the outer edges of the flanges and thereby fusing the flanges and permitting the 35 fused metal to run into the gap and unite the flanges, and effecting a reciprocatory movement between the flanges and their points of contact with the electric circuit transversely across the flanges.
- 40 13. The herein described method of making metal tubes, which consists in bevelling opposite edges of a blank, bending the bevelled edges into flanges, bending the blank into tubular shape with the flanges on the exterior of the shape and defining a triangular rib with the outer edges of the flanges in abutted relation and the adjacent faces of the flanges diverging towards the interior of the tube and defining a gap, including the work piece into an electric circuit with one contact 45 made at the outer edges of the flanges and thereby fusing the flanges and permitting the fused metal to run into the gap and unite the flanges, feeding the tube endwise past its points of contact with the electric circuit, and effecting relative re-
- ciprocation between the flanges and their points of contact with the electric circuit.
14. The herein described continuous method of forming tubes into lengths from a continuous blank, which consists in feeding a continuous blank through a series of roll passes formed by positively driven rolls and thereby beveling opposite edges of the blank, bending the bevelled edges into flanges, and bending the blank into tubular shape with the flanges on the exterior of the shape and defining a triangular rib with the outer edges of the flanges in abutted relation and the adjacent faces of the flanges diverging toward the interior of the tube and defining a gap, directing the moving and shaped blank directly 80 from the last pass to and between idle rotatable electrodes of opposite polarity with one of the electrodes in contact with the flanges and thereby fusing the flanges, whereby the fused metal is permitted to run into the gap and there solidify 85 and unite the edges of the blank.
15. The herein described method of making metal tubes without exerting welding pressure, which consists in taking a tubular blank having its edges spaced and turned outwardly into 90 flanges having their outer edges in abutted relation and defining a gap between the flanges, progressively and continuously fusing the external flanges, and permitting the fused metal to run into the gap and there solidify and unite the edges 95 of the blank.
16. The herein described method of uniting metal parts without exerting welding pressure, which consists in taking parts having their adjacent edges in close proximity but spaced apart 100 and bent outwardly into flanges with their outer edges in abutted relation and defining a gap between them, fusing the flanges, and permitting the fused metal to run into the gap and there solidify and unite the edges of the parts.
17. The herein described method of making metal tubes without exerting welding pressure, which consists in taking a tubular blank having its edges in close proximity and turned outwardly 110 into flanges having their outer edges in abutted relation and the inner faces of the flanges defining a gap, feeding the blank endwise through a supporting seat in an electrode with the out-turned flanges of the blank in wiping engagement with another electrode of opposite polarity to fuse 120 the flanges, and permitting the fused metal to run into the gap and there solidify and unite the edges of the blank.
